UNITED STATES PATENT OFFICE.

FREDRICK OSTERLE, OF PITTSBURG, PENNSYLVANIA.

SEWER-TRAP.

SPECIFICATION forming part of Letters Patent No. 756,046, dated March 29, 1904.

Application filed December 16, 1903. Serial No. 185,392. (No model.)

To all whom it may concern:

Be it known that I, FREDRICK OSTERLE, a citizen of the United States of America, residing at Pittsburgh, in the county of Allegheny and State of Pennsylvania, have invented certain new and useful Improvements in Sewer-Traps, of which the following is a specification, reference being had therein to the accompanying drawings.

10 This invention relates to certain new and useful improvements in sewer-traps; and the primary object of the invention is to provide means whereby water is prevented from backflow from the main sewer to the line leading 15 from the main sewer into the building and the water thereby prevented from backing up into the cellar of buildings.

Briefly described, my invention comprises the embodiment of a pipe-section in which is 20 mounted and securely fastened a ring or annulus made water-tight by the placing of an annular gasket between the periphery of the ring and the inner wall of the pipe-section. This annulus or ring carries a flap-valve or 25 gate which opens freely under the pressure of the water flowing from the house-drain to the main, but closes under backflow of the water from the main sewer, and thus prevents any backflow and consequent overflow into 30 the cellar of the house or building through the drain leading therefrom.

In the accompanying drawings I have shown a practical embodiment of my invention and will describe the same herein in detail without, however, limiting myself to details of construction as shown and described, and in this detail description reference will be had to the accompanying drawings, forming a part of this application, and wherein 35 like numerals of reference will be employed for indicating like parts throughout the different views of the drawings, in which—

Figure 1 is a diagrammatical side elevation showing the adaptation of my invention. Fig. 45 2 is a longitudinal sectional view of a section of pipe, showing the trap in position. Fig.

3 is a transverse vertical sectional view thereof, taken on the line 3 3 of Fig. 2. Fig. 4 is a like view taken on the line 4 4 of Fig. 2.

To describe the invention fully, reference 50 will be had to Fig. 1, in which 1 indicates the main sewer, 2 the sections of pipe forming a conduit leading thereto, and 3 the drain-pipe, leading from a suitable point in the building.

To put my invention into practice, I provide in one of the pipe-sections, either in one of the sections of the conduit formed by pipe 2 or in the drain-pipe, if so desired, a flap-valve or gate. In the present illustration I have shown this flap-valve or gate arranged 55 in one of the pipe-sections 2. It comprises a ring or annulus 4 of slightly less diameter than the bore of the pipe-section and surrounded by a flexible annular gasket 5 to form an air-tight seal between the periphery of the 60 ring or annulus and the inner wall of the pipe-section. This ring is securely fastened in position in the pipe, as by means of screws 6. Hinged to one edge of the ring or annulus 4 is a flap-valve or gate 7, which opens toward 65 the discharge end 8 of the pipe, but closes against the ring or annulus against back pressure. It will thus be observed that while this flap-valve or gate opens readily to allow the water to flow out toward the main sewer it 70 closes tightly under the least back pressure, preventing the water backing into the drain-pipe, and consequently preventing the water rising and overflowing into the cellar of the 75 building.

While described in detail herein in one of its practical forms, it will be evident that in the practice of my invention various slight changes may be made in the details of construction without departing from the general 80 spirit of my construction.

Having fully described my invention, what I claim as new, and desire to secure by Letters Patent, is—

1. In a sewer-trap, a pipe-section, a ring arranged in the interior thereof, screws passing through the wall of the pipe-section into said

ring and a flap - valve hinged to said ring, adapted to open under pressure in one direction and close under pressure in the opposite direction.

5. 2. In combination with a pipe-section, a ring arranged therein, a flexible washer arranged between said ring and said pipe-section, a flap-valve hinged to said ring, and screws passing

through the walls of the pipe - section and through said gasket and into the said ring.

In testimony whereof I affix my signature in the presence of two witnesses.

FREDRICK OSTERLE.
